CONTINUOUS HEATING FURNACE

George R. McDermott, Ottawa Hills, Ohio, assignor to Surface Combustion Corporation, Toledo, Ohio, a corporation of New York

Application October 23, 1939, Serial No. 300,685

1 Claim. (Cl. 263—6)

The present invention relates to a continuous heating furnace having a soaking chamber at one end of a heating chamber—furnaces of this type being employed for heating work pieces to 5 forging or rolling temperatures.

The object of the present invention is to provide for the conveying of the work pieces through the heating chamber and for the pushing of said pieces into the soaking chamber from a point 10 adjacent the discharge end of the heating chamber. More particularly it is the object of the invention to provide a walking beam conveyor which shall be particularly well adapted for conveying work pieces through the heating chamber 15 and for pushing the work pieces into the soaking chamber from the adjacent end of the heating chamber. Other more specific objects will more fully appear hereinafter.

In the accompanying drawing wherein the 20 preferred form of the invention is shown:

Fig. 1 is a vertical longitudinal section with parts in side elevation of a continuous heating furnace embodying the present invention;

Fig. 2 is a fragmentary sectional view, on line 25 2—2 of Fig. 2, the view showing only one-half of the width of the furnace;

Fig. 3 is a fragmentary sectional view of a detail, the view being taken on line 3—3 of Fig. 1;

Fig. 4 is a fragmentary side elevation of a detail;

Fig. 5 is a plan view of Fig. 4, and

Fig. 6 is a diagram of certain movements of the walking beam.

The furnace comprises a main heating chamber 10, a soaking chamber 11, upper and lower burners 12 and 13 firing into the chamber 10 by way of upper and lower firing ports 14 and 15 and a burner 16 firing into the soaking chamber by way 35 of a port 17, it being understood that there is a row of each of said burners and ports and that the purpose of the soaking chamber is to allow the temperature of the work pieces to become equalized after having been passed through the heating chamber 10. A side door 18 in the soaking chamber serves for the removal of the work pieces.

Extending upwardly from the floor of the heating chamber longitudinally thereof from the charge end 19 to the hearth 20 of the soaking 50 chamber is a plurality of laterally spaced piers or tracks 21 whereon the work pieces (indicated at W in Fig. 2) are supported when they are not supported on the lift rails of a walking beam generally indicated at 22. As shown in Fig. 2 each 55 half of the furnace may have its own walking

beam thereby permitting two independent rows of work pieces to be passed through the furnace.

In accordance with the present invention the walking beam comprises a pair of lift rails 23, a row of inverted U-shape pedestals 24 for each rail, and a platform 25 on which the pedestals are supported. It will be understood that the walking beam is reciprocated both longitudinally and vertically. The means for reciprocating the walking beam may be of any preferred type and is here shown as comprising a horizontally movable undercarriage 26 on which are inclined blocks 27 on which ride rollers 28 carried by the platform 25. To raise and lower the walking beam the platform 25 is held against longitudinal movement while the carriage 26 is moved back and forth as by a cylinder 29 and to move the beam horizontally the platform 25 and the carriage 26 are moved as a unit as by a cylinder 30.

In the cylinder arrangement shown, the cylinder 30 is anchored to a fixed base structure 31 and its piston rod 30' is secured to a cross piece 32 which forms part of a slid able carriage 33 from which rises a standard or standards 34 which is connected by a link or links 35 to the adjacent end of the walking beam platform 25. The cylinder 29 is fixed to the top side of the slid able carriage 33 and its piston rod 29' is secured to a cross piece 36 which forms part of the extended end of the undercarriage 26.

Welded to the top of each lift rail 23 is a wear strip 37. The lift rails are tubular and depending from the leading end of each rail is a depending tubular post 23' to permit the passage of cooling water therethrough. Each pedestal 24 consists of a pair of radially-spaced upright tubes 240 mounted at their lower ends in saddles 40 secured to the platform 25 and cross connected at their tops by a tubular connection 241 to permit cooling water to be flowed from one tube to the next. 40 As a further protection against overheating, the parts are covered with a heat insulating refractory material 38 held in place by radial pins 39 on the tubular members.

In order that the cooling water may be flowed 45 through the pedestals 24 in succession, the lower ends of adjacent tubes 240 of adjacent pedestals are cross connected by tubular elements 24'. As shown in Fig. 2 the tubes 240 may be welded as at 40' to upright extensions 24" of the lower 50 cross connection 24', the cross connections in such case being seated in and welded to the saddles 40. The floor of the heating chamber is provided with slots 41 through which the legs of the pedestals 24 extend and these slots are cov- 55

ered over with slideable plates 41 through which the said legs extend.

The use of inverted U-shape pedestals 24 for supporting the lifting rails 23 is an important feature of the invention because in addition to being of simple construction and therefore relatively inexpensive to make, they give to the walking beam as a whole a certain degree of resiliency in a longitudinal direction which is very desirable in absorbing shock resulting from the stopping of the beam at the ends of its stroke. Such longitudinal bracing as may be required is provided outside of the heating chamber by struts 50 and 51.

In accordance with the present invention the walking beam 22 not only serves to transport the work pieces towards the hearth 20 but also to push the work pieces onto the hearth from a point adjacent the front end of the same. The mode of operation is best described in connection with Fig. 6. In this figure the walking beam is in elevated position and at the forward end of its stroke. The full stroke of the beam may be considered as the distance between the points *a* and *b*. As the walking beam moved from point *a* to *b* the work piece or pieces *W*' already on the track 21 in advance of the beam were pushed forward as the beam advanced. Having advanced to the limit of its forward motion the beam may be lowered and moved back to the position shown by the broken-line rectangle *c* from which position it is moved upwardly and then forwardly as will now be readily understood. However, before the walking beam is lowered from its forward limit of movement it is preferred that it be moved rearwardly a relatively short distance, say to the point *d*, before it is lowered. By thus causing the beam to move rearwardly to the point *d* before being lowered, rubbing of the front end of the beam against the nearest work piece which was pushed is avoided and it is assured that said particular work piece will not interfere with the proper lowering of the foremost work piece on the walking beam as the latter is lowered, and less attention need be paid to the spacing of the work pieces on the walking beam at the charge end of

the furnace. It will be readily appreciated that the partial return movement of the walking beam may be readily accomplished by admitting a small amount of motive fluid (ordinarily oil under pressure) to the stroke control cylinder 28 while at the same time preventing relative movement between the walking beam and the undercarriage 26. In order to prevent damage to front end of the walking beam and more particularly the down-comer 23' of the lifting rail, a wear or pusher head 43 is secured to the upper corner of the beam as will be readily understood by reference to Figs. 4 and 5.

What I claim is:

A furnace for the heating of metal objects to forging or rolling temperatures comprising an elongated chamber defined in part by a floor which at the front end of the chamber is at a higher level than at the rear end thereof and a rear end wall having an opening a substantial distance above the lowest level of the floor for the exit of heated objects from the chamber, means forming a trackway leading from said opening to the front end of the chamber for supporting the objects to be heated at a level above said floor, means including burners firing into said chamber through said wall at a level below said opening for heating the objects supported on the trackway, and means for pushing the objects toward said opening from a point intermediate the ends of the chamber and for bodily conveying the objects to said point from the front end of the chamber, said means comprising a vertically and horizontally movable elongated support underlying the floor of the chamber in parallelism with said trackway, a plurality of laterally spaced rows of longitudinally spaced pedestals mounted on said support and extending upwardly into said chamber through the floor thereof, an elongated member mounted on top of each row of pedestals, and said pedestals each consisting of a pair of radially-spaced upright tubes and a tubular cross connection between the upper ends of the tubes to permit cooling fluid to be flowed from one tube to the next.
